Primary Examiner—Caron D. Veynar*Assistant Examiner*—Sydney R Buffalow(74) *Attorney, Agent, or Firm*—Fitch, Even, Tabin & Flannery(57) **CLAIM**

The ornamental design for a food merchandiser, as shown and described.

DESCRIPTION

FIG. 1 is a right-front perspective view of a food merchandiser showing our new design; and,

FIG. 2 is front elevational view thereof.

The surfaces or portions of the food merchandiser not shown in the drawings or described in the specification form no part of the claimed design.

The broken lines showing of a microwave oven on the lower left, and a handled, hinged freezer door and support legs on the lower right, are for illustrative purposes only and form no part of the claimed design.
